(No Model.)

C. McNEIL.
MACHINE FOR SEWING LOOPED FABRICS.

No. 556,585.

Patented Mar. 17, 1896.

UNITED STATES PATENT OFFICE.

CHESTER MCNEIL, OF CHICAGO, ILLINOIS, ASSIGNOR TO THE UNION
SPECIAL SEWING MACHINE COMPANY, OF SAME PLACE.

MACHINE FOR SEWING LOOPED FABRICS.

SPECIFICATION forming part of Letters Patent No. 556,585, dated March 17, 1896.

Application filed January 18, 1892. Serial No. 418,417. (No model.)

To all whom it may concern:

Be it known that I, CHESTER MCNEIL, a citizen of the United States, residing at Chicago, in the county of Cook and State of Illinois, have invented certain new and useful Improvements in Machines for Sewing Looped Fabrics, of which the following is a description, reference being had to the accompanying drawings and to the letters and figures 10 of reference marked thereon.

My invention relates to improvements in sewing-machines, and particularly to those machines designed for sewing looped fabrics; and it consists in the matters hereinafter 15 described and referred to in the appended claims.

My invention is illustrated in the accompanying drawings, in which—

Figure 1 is a side elevation of my improved 20 machine; and Fig. 2 is a view, partly in section, on line $x x$, Fig. 1.

In the drawings the details of construction of the sewing, trimming, and overseaming mechanisms are the same as shown and described in Letters Patent No. 407,286 of July 25 16, 1889, granted to H. H. Fefel; but it will be understood that as far as the particular sewing, trimming, and overseaming mechanisms are concerned other apparatus accomplishing the same purpose might be substituted 30 for that herein shown.

Referring now to the drawings, A represents the main part or frame of the machine attached to a suitable bracket, as A'.

35 1 represents an overhanging arm, herein shown as the goose-neck, and 2 the longitudinally-extending arm which supports the cloth-plate 3. The main driving-shaft 4 is herein shown as arranged vertically and having 40 bearings on the arm 1 and support 2.

C is the needle-arm lever pivoted to the frame of the machine and actuated from the main driving-shaft by the usual system of eccentrics and connecting-rods. Connected 45 to this arm C, so as to reciprocate simultaneously and in a longitudinal direction, are the needle-bars 14 and E', carrying, respectively, the ordinary straight-sewing needle *a* and the overseaming-needle *b*. The lower end of the 50 main shaft 4 carries a looper 5 and also an eccentric, which operates a horizontally-moving

plate 7, to which is attached one blade B of a trimmer. Co-operating with this blade B is a second blade B', which, as shown, is stationary. This shaft 4 also carries an eccentric 55 which is encircled by the yoke 15 of a rod 16, connected by a universal joint with a lever D, upon the outer end of which is a looper E, so disposed as to move in oblique directions through the cloth-plate 3. Operated 60 by suitable connections from the main shaft 4 is a rock-shaft F, through which motion is communicated to a spreader-hook G, the same having its points so disposed that at a proper time it takes a loop of thread from the looper 65 E and conveys it to the path of the reciprocating needle *b* for forming an overseam on the edge of the fabric.

It is not deemed necessary to further describe the construction of the particular mechanisms for sewing, trimming, and overseaming the fabric, since they are the same in respect to detail as in the patent above referred to, the difference consisting in the various arrangements of parts—that is, in the setting 75 of the parts to operate just at right angles to the positions which they occupy in the patent mentioned.

I will now proceed to describe my other improvements, whereby the machine shown is 80 adapted for use particularly in sewing looped fabrics.

While the support for the rotatable material-carrying cylinder is in the present case a vertical overhanging arm identical with the 85 goose-neck of the machine, and while this construction is possibly preferable because of the greater compactness of the machine and is therefore claimed by me, nevertheless it will be understood that in its broadest sense 90 the invention is not limited to such construction, but the cylinder may be attached to any other portion of the head of the machine or to a separate overhanging arm, bracket, or support.

Attached to the overhanging arm (herein shown as the goose-neck or head of the machine) is a cylinder H, having suitable impaling-pins upon which the goods to be sewed are placed. This cylinder is rotated in a horizontal plane from the main shaft 4 through 95 the connecting-shafts and gear-wheels shown 100

in Fig. 1. By this arrangement it can be seen that the material can be placed on the cylinder and fed to the sewing mechanism with the greatest ease.

5 I represents the presser-foot, which is provided with suitable openings for the passage of the needles *a* and *b* and trimmer knife-blade *B*. Said presser-foot between the trimmer and overseaming-needle *b* is cut away to 10 allow of the operation of a rotatable brush *K*, which removes the lint from the fabric arising from the action of the trimmer. This brush is herein shown as mounted on one end of a suitable shaft *c* journaled in suitable 15 bearings on the throat-plate and having near its opposite end a belt-pulley *d*, over which runs a belt *e* driven from the main shaft 4 through the bevel gear-wheels *f g*.

Various modifications and changes in the 20 details of construction of the herein-described machine may be made without departing from the spirit of my invention.

It will of course be understood that I propose to use in connection with the cylinder herein 25 illustrated the usual co-operating parts, such as stripping-plates, impaling mechanism, &c., which are common in machines for sewing looped fabrics.

I claim as my invention—

30 1. In a machine for sewing looped fabrics in combination with stitch-forming mechanisms for straight sewing and overseaming respectively, a trimmer between the two stitch-form-

ing mechanisms, a brush between the trimmer and overseaming mechanism, and a rotatable material-carrying cylinder for holding the material and feeding it into position to be operated upon; substantially as described.

2. In a machine for sewing looped fabrics in 40 combination with stitch-forming mechanism comprising a needle for straight sewing and a needle for overseaming, a trimmer between the two needles, a brush between the trimmer and overseaming-needle and a rotatable 45 material-carrying cylinder attached to the head of the machine whereby the material is supported and fed into position to be operated upon; substantially as described.

3. In a machine for sewing looped fabrics, a 50 main vertical shaft, a vertical overhanging arm, a horizontally-rotatable material-carrying cylinder attached to said overhanging arm, a horizontally-reciprocating needle for forming a straight stitch, a trimmer behind 55 said needle, a second horizontally-reciprocating needle for overseaming arranged behind said trimmer and a rotating brush between the trimmer and overseaming-needle; all substantially as subscribed.

In testimony whereof I affix my signature in presence of two witnesses.

CHESTER MCNEIL.

Witnesses:

W. S. NORTH,
MORTON MCNEIL.
